UNITED STATES PATENT OFFICE.

WALTER C. KIESEL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 31, 1919. Serial No. 334,638.

To all whom it may concern:

Be it known that I, WALTER C. KIESEL, a citizen of the United States, residing at New York, in the county of New York, State 5 of New York, have invented certain new and useful Improvements in Telephone-Exchange Systems, of which the following is a full, clear, concise, and exact description.

This invention relates to telephone exchange systems, and more particularly to 10 private branch exchange systems wherein both manual and automatic facilities for interconnection are provided.

In such systems it is the usual practice 15 to provide subscribers, desiring both manual and automatic facilities for interconnection, with two telephone sets, one of the manual type and the other of a type so arranged that the subscriber may himself make the 20 selection of the desired subscriber, an impulse sender being most commonly used.

The object of this invention is to provide 25 a single telephone set for extending a connection from a calling line to a called line over either a manual or an automatic link 30 circuit and to provide means whereby said calling line may be signaled during the extension of a connection over said automatic link circuit.

A further object is to provide in a system 35 of this character, means whereby, during the existence of a connection supervised by an operator, a subscriber may hold such connection, call another station over automatic 40 switching apparatus and after completion of conversation therewith resume conversation over the supervised connection.

In accordance with the objects of this invention, a subscriber's telephone set is provided 45 with means whereby he may selectively extend his line to a manual switchboard or to automatic switching apparatus. When the telephone set is connected to the latter, a signaling device located at the subscriber's station is automatically placed 50 under the control of the operator at the manual switchboard. This signaling device serves also to hold the connection over the supervised connection when the switching device is operated for the purpose of making 55 a call over the automatic switching mechanism.

A further feature is in a supervisory means actuated in response to the plugging

into the jack in which such a subscriber's 55 station normally terminates for indicating to the operator that such a station is busy talking over the automatic link circuit.

Other novel and useful features will be made clearer in the following specification 60 and the appended claims.

In the drawing, Fig. 1, represents diagrammatically the circuits and apparatus embodied in this invention. That portion of the drawing indicated by the dotted lines in the upper left-hand corner of the drawing represents the apparatus necessary for a station equipped with means for extending the line to a manual switchboard or to automatic 65 switching apparatus. A represents an ordinary subscriber's set, 5 is a switching device which for convenience is here shown as a key, S represents an ordinary subscriber's impulse sender which may be of any type, and a signaling means is here shown as a 70 ringer 56. The subscriber's set A is normally connected through the switching device 5 to a jack 7 located at the P. B. X. switchboard. Substation B represents a line not equipped with special service features 75 and has its jack multiplied to the terminals of a contact bank.

Fig. 2 represents diagrammatically a cord circuit of a well-known type and is used for manually interconnecting the substations 80 at the switchboard.

Fig. 3 represents diagrammatically a substation of the P. B. X. system not arranged for special service features. The jacks in which such lines terminate are multiplied 85 to the terminals of a contact bank, having 90 an automatic switch cooperating therewith.

The invention will be more readily understood from a detailed description of the operation of the system. 95

The party at substation A desiring to call, for example, station B, operates the locking key 5 and then removes the receiver from the switchhook. Only one subscriber's station of the system is assumed to be equipped 100 with the special service features. If there were a plurality of such substations each would be equipped with a line finder (not shown). Operation of key 5 extends the calling line to the connector C. The stepping relay 8 thereof is energized and by attracting its armature energizes a slow release relay 9. This relay in attracting its 105

right armature interposes a break in the circuit for release magnet RM and at its right armature and front contact connects the back contact of stepping relay 8 to the primary magnet PM of the connector. The calling party now operates his sender S to transmit the tens digit of the desired number. The sender in restoring, interrupts the line circuit a number of times corresponding to the tens digit of the desired number. Upon each retraction of the stepping relay 8, an impulse is sent over a circuit to primary magnet PM to position a set of brushes 11, 12 and 13 in operative relation to the group of terminals containing those of the wanted line. This circuit extends from free pole of battery, magnet PM, side switch arm 14, back contact and armature 50 of busy relay 55, conductors 15 and 46, right armature and front contact of relay 9, and armature and back contact of relay 8 to ground. The slow relay 16 in parallel with magnet PM energizes upon the first impulse, and being slow-acting remains energized during the transmission of the impulses. When the sender S restores and maintains the line circuit closed, relay 8 remains energized. After an interval, the slow relay 16 becomes deenergized opening the circuit of magnet 17 which was closed when this relay was energized. The escape magnet 17 in deenergizing moves the side switch into position 2. In this position the secondary magnet SM is substituted for the primary magnet PM. The calling party now operates his sender to transmit the units digit of the desired number. The secondary magnet SM in response to these impulses steps the brushes 11, 12 and 13 over the terminals of the selected group. The slow relay 16 is again energized in parallel with the secondary magnet SM and again energizes the escape magnet 17. When the sender S restores and maintains the line circuit closed, the slow relay 16 after an interval deenergizes, opening the circuit of escape magnet 17 which moves the side switch into position 3.

Assuming that the terminal 40 of the line upon which the connector has been set is idle, the following circuit is closed for the escape magnet 17 to close the ringing circuit: grounded battery, escape-magnet 17, arm 22, armature and back contact of ringing cut-off relay 29, conductors 23, 24 to ground at the left-hand armature and front contact of relay 9. Magnet 17 in attracting its armature closes the ringing circuit as follows: ground, generator 25, battery, relay 29, armature and front contact of magnet 17, arm 26 and its third contact, brush 12, terminal 43, through the substation B, terminal 42, brush 11, arm 31 and its third contact to ground.

When the party at substation B removes his receiver, the relay 29 energizes, opening

the circuit of escape magnet 17, which thereupon deenergizes and moves the side switch into position 4. In moving out of position 3, the ringing circuit is opened and in position 4 talking current is supplied to the called party over the following circuit: grounded battery, retardation coil winding 33, conductor 34, arm 31 and its fourth contact, brush 11, terminal 42, through substation B, terminal 43, brush 12, arm 26 and its fourth contact, conductor 35, retardation coil winding 36 to ground. Talking current is supplied to the calling party over the windings of relay 8. The calling and called ends of the talking circuit are conductively separated and inductively united by condensers 37 and 38.

Assume now that the line upon which the connector is set is busy. The test terminal 40 in such event would have a battery potential thereon, either due to another connector being set upon said terminal or due to battery being supplied from the sleeve of a cord circuit which had been plugged into a jack of the line at the switchboard. Going back to that point in operation where the calling party transmits the units digit of the called number, it will be remembered that the slow relay 16 is energized in parallel with the secondary magnet SM, and that this relay at its armature and front contact completes a circuit for the escape magnet 17, the side switch being at this time in position 2. When the connector brushes 11, 12 and 13 reach the selected set of terminals 42, 43 and 40, and before the slow relay 16 has had time to retract its armature, a circuit is closed in position 2 of the side switch over terminal 40 of the busy line which has battery thereon, brush 13, side switch arm 41 and its second contact, right winding of relay 55 to ground through contacts 98 and 99. Relay 55 in attracting its inner armature locks itself up over a side switch arm 45 and its second contact. At armature 51 relay 55 closes a circuit to maintain the escape magnet 17 energized to hold the side switch in position 2. At armature 50 it interposes a break in the circuit of magnet SM to prevent the calling subscriber from transmitting any more impulses and at its outer left-hand armature connects a source of busy tone current 42 over side switch arm 48 in its second position to the conductor 35, and thence to the calling line to inform the calling party that the desired line is busy. When the calling party replaces his receiver, relays 8 and 9 release and the connector release magnet RM is energized over the following circuit: free pole of battery, magnet RM, contact PON, right armatures and back contacts of relays 9 and 8 to ground. Magnet RM restores the connector and when the brush shaft thereof reaches its normal position, it opens contact PON and unlocks the

release magnet. This magnet in operating also restores the side switch in a well-known manner.

Suppose now that during the establishment of a connection over the automatic switching mechanism with some station of the private branch exchange system, a station at the central office desires connection with substation A. The operator places the calling plug 21 in jack 7, which causes the energization of relay 19, and of the bridged relay 18 in the cord circuit over the following circuit: ground, left-hand winding of relay 18, tip of plug 21, tip of jack 7, front contact and armature of relay 19, ringer 56, contact and upper outer spring of switching device 5, conductor 10, ring of jack 7, ring of plug 21, and right-hand winding of relay 18 to grounded battery. Energization of relay 18 causes lamp 17 of the cord circuit to light. This signifies to the operator that substation A is busy talking over the automatic switching apparatus to some other station of the private exchange system; she, therefore, informs the calling party that substation A is busy. Suppose on the other hand that the incoming call for substation A is a very important one, or is perhaps a long distance call, the operator will in such case depress her ringing key (not shown), and send a source of ringing current to substation A over the following circuit: ring of plug 21, ring of jack 7, conductor 10, uppermost spring and contact of switching device 5, ringer 16, contact of relay 19 (condenser 20 being short-circuited over conductor 6), tip of jack 7, tip of plug 21 to source of ringing current. The ringer 56 will be operated and substation A will, therefore, be notified that a very important call for him has arrived. Conversation with substation B will then be terminated, switching device 5 will be restored and substation A is ready to talk with the calling line. Again suppose that a conversational connection exists over the manual link circuit M between subscribers A and D, or between subscriber A and a party at the central office, and that subscriber A desires information from some other substation of the private branch exchange system. Operation of switching device 5 will bridge ringer 16 across the line leading to the cord circuit M so that no disconnect signal will be given to the operator at the switchboard. Impulse sender S will then be operated, connection completed over the automatic switching mechanism, and after information has been obtained or instructions have been given, the subscriber of substation A again restores switching device 5, reconnects his substation to substation C, and resumes conversation. After completion of conversation restoration of receiver upon the receiver hook gives the disconnect signal to the operator in the usual

manner who thereupon disconnects and the system is ready for another call.

What is claimed is:

1. In a telephone exchange system, a plurality of subscribers' lines, a manual and an automatic connecting circuit for extending a calling one of said lines to a called one of said lines, subscriber controlled switching means for selectively extending the calling line over said manual or said automatic connecting circuit, and a signaling device for the calling line placed in operative relationship with one of the connecting circuits in response to the actuation of the switching means to connect the calling line to the other of the connecting circuits. 70

2. In a telephone exchange system, a calling line, a signaling device associated with said calling line, a called line, a manually controlled circuit for interconnecting said lines, a circuit controlled by the calling line for establishing a connection with the called line independently of the manually controlled circuit, and means for actuating said signaling device independently of the conductors of said calling line over the manually controlled circuit when said calling line is connected to the independently controlled circuit. 85

3. In a telephone exchange system, a calling line, a called line, a manually controlled link circuit for interconnecting said lines, an automatic link circuit controlled by the calling line for establishing a connection with the called line independently of the manually controlled circuit, switching means at the calling line for selectively connecting said line with one or the other of said link circuits, and a signal device at the calling station placed under the control of the manually controlled circuit in response to the actuation of the switching means to connect the calling line with the automatic link circuit. 100

4. In a telephone exchange system, a calling line, a station therefor, a switching device at the calling station, a called line, automatic switching mechanism for interconnecting said lines when said switching device is in one position, a manual circuit for connecting said lines when said switching device is in another position, and means for signaling the calling station over the manual connecting circuit when the station of the calling line is connected to the automatic switching mechanism. 110

5. In a telephone exchange system, a calling line, an operator's position, a switching device having a plurality of positions for connecting said line to a corresponding plurality of other lines, one of said other lines comprising a signaling conductor and a pair of talking conductors, said one of said other lines extending from said switching device to said operator's position, and supervisory 125

- means at said operator's position controlled over said signaling conductor for indicating to the operator the position of said switching device. 45
- 5 6. In a telephone exchange system, a manual switchboard, operators' cord circuits thereat, a calling line, a switching device having a plurality of positions for connecting said calling line to a corresponding plurality of other lines, one of said other lines extending from said switching device to said manual switchboard and comprising a signaling conductor and a pair of talking conductors, and supervisory means associated with said cord circuits controlled over said signaling conductor for indicating to the operator the position of said switching device. 50
- 10 7. In a telephone exchange system, a manual switchboard, a plurality of telephone lines terminating in jacks therein, link circuits for interconnecting said lines, a contact bank having its terminals multipled to said jacks, an automatic switch associated therewith, a calling line having two branches, one of said branches terminating in a jack in said switchboard and the other in said automatic switch, a switching device for extending said calling line to said manual switchboard or to said automatic switch, and means for signaling said calling line from said manual switchboard during the extension of a connection over said automatic switch. 60
- 15 8. In a telephone exchange system, a calling line, a called line, a plurality of other lines, all of said lines terminating at the same manually operated switchboard, a manual link circuit for connecting said calling line with said called line, an automatic link circuit for connecting said calling line with any of said other lines, and means for holding a connection over said manual circuit during the establishment of a connection to any of said other lines over said automatic link circuit, said means serving as a signaling device to attract the attention of the subscriber of the calling line when a call is initiated over the automatic link circuit. 65
- 20 9. In a telephone exchange system, a calling line, a called line, a plurality of other lines, all of said lines terminating at the same manually operated switchboard, a manual link circuit for connecting said calling line with said called line, an automatic link circuit for connecting said calling line with any of said other lines, a switching device arranged in its normal position to extend said calling line to said manual link circuit and in its operated position to said automatic link circuit, and holding means for said manual link circuit operative when said switching device is operated to extend said calling line to said automatic link circuit. 70
- 25 10. In a telephone exchange system, a plurality of lines, a manual and an automatic connecting circuit for extending one of said lines to another of said lines, a switching device for the calling line for enabling the calling subscriber to selectively extend his line over one or the other of said connecting circuits, and a signaling device placed in operative relationship with one of said connecting circuits in response to the seizure of the other of said connecting circuits. 75
- 30 In witness whereof I hereunto subscribe my name this 30th day of October A. D., 1919. 80
- 35 WALTER C. KIESEL.
